[57] **CLAIM**

The ornamental design for a display package for lug nuts, as shown and described.

DESCRIPTION

FIG. 1 is a perspective view of a display package for lug nuts showing my new design;

FIG. 2 is a front elevational view thereof;
FIG. 3 is a rear elevational view thereof;
FIG. 4 is a left side elevational view thereof; the right side elevational view being a mirror image thereof;
FIG. 5 is a top plan view thereof;
FIG. 6 is a bottom plan view thereof;
FIG. 7 is a perspective view thereof, similar to FIG. 1 with lug nuts shown in package in broken lines;
FIG. 8 is a perspective view thereof; shown in an open position with lug nuts shown in package in broken lines;
FIG. 9 is a perspective view thereof, similar to FIG. 8, showing a slightly different form of lug nuts shown in broken lines;
FIG. 10 is a perspective view thereof, similar to FIG. 8, showing a further modified form of lug nuts shown in broken lines;
FIG. 11 is a perspective view of a second embodiment of a display package for lug nuts;
FIG. 12 is a front elevational view of FIG. 11;
FIG. 13 is a rear elevational view of FIG. 11;
FIG. 14 is a right side elevational view thereof, the left side elevational view being a mirror image thereof;
FIG. 15 is a top plan view thereof;
FIG. 16 is a bottom plan view thereof;
FIG. 17 is a perspective view similar to FIG. 11 with lug nuts shown in package in broken lines;
FIG. 18 is a perspective view similar to FIG. 17 shown in an open position with lug nuts shown in package in broken lines;
FIG. 19 is a perspective view thereof similar to FIG. 11 and showing a modified form of lug nuts in broken lines; and,
FIG. 20 is a perspective view thereof, similar to FIG. 18, showing a further modified form of lug nuts shown in broken lines.

The broken lines showing lug nuts in FIGS. 8-10 and 18-20 is for illustrative purpose only and forms no part of the claim. The inside portions of the claimed design not shown in FIGS. 8-10 and 18-20 are disclaimed. FIGS. 2-6 and 12-16 are drawn in reduced scale.
